CONTROL SWITCH

Richard K. Engholdt, Milwaukee, Wis., assignor
to Milwaukee Gas Specialty Company, Milwaukee, Wis., a corporation of Wisconsin

Application May 25, 1940, Serial No. 337,178

12 Claims. (Cl. 200—153)

The present invention relates to a control device, and more particularly to a switch controlled by condition responsive means.

The principal field of utility of the invention is in connection with fuel burners having a fuel supply pipe leading to the burner, a valve, such as a solenoid or motor valve, in the fuel supply pipe, and a safety shutoff feature adapted to effect operation of the valve to close position to shut off the supply of fuel to the burner when the pilot light associated with the burner goes out, and operative to prevent the valve from being opened until the pilot light is ignited. It is to be understood, however, that the invention is not limited to this particular field of utility but may be employed in all similar work as suitable or desired.

For example, the control switch of the present invention may be employed in conjunction with valves that require current or power for both opening and closing, and the switch and control features of the present invention may be used for controlling other circuits than the particular circuit shown and described—for example, for controlling alarm circuits, and for all similar purposes.

One of the main objects of the invention is to provide in a device of the class described an electromagnet or other suitable holding means, an armature or other means, operating means for cocking the armature or other means to the position in which it is held by the holding means, a switch movable with the cocking means in the cocking operation, and improved means for actuating the switch to one position when the holding means is effective to accomplish its holding function and the cocking means is released, which improved means is also effective to actuate the switch to its other position when the holding means is rendered ineffective to accomplish its holding function, for example by extinguishment of the pilot light.

It is another object of the invention to provide improved means of the character set forth which will not operate the switch, for example, to close the circuit for opening the valve until the pilot light is ignited and the holding means is operative to accomplish its holding function.

Another object of the invention is to provide in a device of the character described a snap-acting toggle switch and improved actuating means therefore for accomplishing the results set forth.

Another object of the invention is to provide in a device of the character described improved

means for indicating the position of the switch.

Another object of the invention is to provide an improved thermoelectric safety control and switch combination of relatively simple and inexpensive construction, and which may be installed and operated conveniently and effectively; also a device of the character described composed of relatively few parts and adapted for convenient and expeditious manufacture and assembly and which will operate quickly, positively, and effectively, and will fail "safe." If the valve under the control of the switch is closed, it will remain in that position against being opened by the cocking operation until a certain condition is set up, for example, until the pilot burner is ignited and the holding means rendered effective, and if the valve is in open position, it will immediately move to closed position upon termination of said condition, i. e., when the pilot light goes out.

While the particular structural features by which I obtain a device of the character set forth and the switch entering into the combination are important features within the more specific aspects of the invention, it is to be understood that these features may be varied within the broader aspects of the invention.

Further objects and advantages of the invention will be apparent from the following detailed description, taken in connection with the accompanying drawings in which:

Figure 1 is a more or less diagrammatic view showing an embodiment of the invention in a fuel burner supply system;

Figure 2 is a front view of the control device of the present invention, with parts thereof in section;

Figure 3 is a fragmentary detail view showing the guide bracket for the actuator member;

Figure 4 is a fragmentary view, partially in elevation and partially in section, taken from one side of the device as viewed in Figure 2; and

Figure 5 is a fragmentary view taken from the same direction as Figure 2 and showing the switch in a different circuit controlling position.

The invention can be embodied in a wide variety of forms, and is adapted for use with a wide variety of control systems. It is, as previously stated, particularly applicable for use as a part of a safety pilot control in a fuel burner control system and has been shown as embodied for such use.

In Figure 1 of the drawings, a gas or other fuel burner of any suitable or preferred type is con-

ventionally illustrated at 10. The burner 10 may be the burner of a room or space heater, water heater, floor furnace, gas range, or any other burner. A gas or other fuel supply pipe 11 leads to the burner 10 for the delivery of gas or other fuel thereto—for example, through a mixing chamber (not shown) to which air is admitted in the usual way, as well understood in the art.

The fuel supply pipe 11 has a power actuated shutoff valve 12, such as a solenoid or motor valve. 10 The valve 12 is shown as comprising a valve body 13 and a hood 14 having suitable power operated valve actuating means therein. A step-down transformer 15 supplies power for the operation of the system. This transformer comprises a line voltage primary 16 and a low voltage secondary 17. The primary 16 is connected to line wires 18 leading to any suitable source of current or power (not shown). The valve actuating means for the valve 12 is connected into the secondary circuit 19. The control switch of the present invention is also connected into the secondary circuit 19 as will presently more fully appear.

For purposes of illustration, it may be assumed that the valve 12 is of a character to be actuated to open position by closing of the circuit 19 and to be held in open position to supply fuel or operative energy to the burner 10 as long as the circuit 19 is closed. The valve 12 may have spring means, or other suitable means, for actuating the valve to closed position to shut off the supply of fuel to the burner 10 when the circuit 19 is opened or interrupted.

The control switch is shown as located within a housing 20. Secured to the rear wall of the housing 20 is an angle-shaped guide bracket 21. An actuator member or operating lever 22 is slidably mounted in the outwardly extending leg of the guide bracket 21 and in the base or wall 23 of the housing 20. The particular actuator member shown in the drawings comprises a pair of members having their outer ends secured together and operating slidably through the opening in the wall 23. The inner ends of these members are forked apart, and the inner or rear arm of the forked part is shown as the part which is slidably mounted in the bracket 21. The outer end of the actuator member is provided with an operating button 24.

The holding means is shown in the form of an electromagnet also located within the housing 20. The electromagnet selected for illustration comprises a magnet frame 26 secured, for example, to a terminal bushing 28 in the manner more fully disclosed in my copending application Serial No. 328,923, filed April 10, 1940. The coil 30 of the electromagnet is wound around the legs of the magnet frame 26. The bushing 28 is shown as externally threaded for threaded engagement with a nut 31 by means of which the bushing is clamped to the outer end of the electromagnet and armature enclosing and mounting cup 32. The externally threaded outer end of the bushing 28 extends outward through an opening in the wall 34 of the housing 20, and has threaded engagement with a nut 35 by means of which the bushing is clamped to the wall 34.

The pilot burner 36, which is located in juxtaposition to the main burner 10 to maintain a pilot light for lighting the main burner, is supplied with gaseous fuel by a pilot supply pipe 37. The pilot supply pipe 37 may be connected with the main supply pipe 11 anterior of the valve 12, or

it may be supplied with fuel for delivery to the pilot burner in any other desired manner.

A thermocouple, indicated at 38, is placed in position so that the hot junction 40 thereof will be heated by the pilot flame as long as the pilot flame is burning. The construction of the thermocouple may be similar to that more fully disclosed in Oscar J. Leins Patent No. 2,126,564, granted August 9, 1938, or the construction of the thermocouple and the leads therefor may be of any other suitable or preferred form.

For the purpose of the present description, suffice it to state that the particular thermocouple 38 selected for illustration comprises an outer tubular metallic thermocouple element 42 and an inner metallic thermocouple element 43 of different thermoelectric characteristics. The inner thermocouple element 43 is joined at one end to the outer end of the outer thermocouple element 42 to form the thermojunction which is placed in position to be heated by the pilot light at the pilot burner 36. An inner lead conductor 44 is joined to the inner thermocouple element 43 to form an internal thermojunction 45, and an outer tubular lead conductor 46 is connected to the outer thermocouple element 42, for instance, through a sleeve 47, to form a third thermojunction 48. The inner lead conductor 44 is insulated from the outer lead conductor 46, for instance, by a wrapping of insulation on the inner lead conductor as indicated at 50.

A quick detachable or removable connection is preferably provided between the opposite ends of the leads 44 and 46 and the coil 30 of the electromagnet. This removable lead connection may be of the form disclosed in my copending application above identified, and is illustrated in that form, or it may be of any other suitable or preferred form. Suffice it, for purposes of this description, to state that the inner lead 44 has a connector cone 52 which seats in the correspondingly recessed outer end of the terminal tip 53 and is clamped in contact therewith by a connector sleeve 54. The adjacent end of the outer tubular lead conductor 46 is connected in circuit with one side of the coil 30 through the connector sleeve 56 and the bushing 28, and the other side of the coil is connected to the terminal tip 53, the parts being suitably insulated as shown.

The electromagnet has an armature 60 attached to the end of a stem 62, if desired, in a manner to permit self-accommodation of the armature, when in attracted position, to the pole ends of the magnet frame 26. The electromagnet and armature are enclosed within the cup 32. The inner end of the cup 32 is closed by guide and closure means shown as comprising a cup-shaped bearing plate 63 having pressed fit or other suitable engagement in the inner end of the cup 32. A spring seating disk is shown at 64, and suitable sealing material, such as felt packing or the like, as indicated at 65, is provided between the members 63 and 64 and around the stem 62 to seal the interior of the cup 32 along this stem.

The end of the stem 62 opposite the end on which the armature 60 is mounted is secured by a pin 69 in a member 70. This member 70 operates between the arms of the forked inner end of the actuator member 22. The arms of the forked inner end of the member 22 are slotted at 71, and a pin 72 extends through the member 70 with its opposite ends operating slidably in the slots 71. The opposite ends of the pin

72 may be headed as shown in Figure 4, or provided with other stop means for preventing displacement of the pin.

The switch, designated in its entirety at 74, is a toggle switch of existing form except for 5 the manner in which it is combined with the other parts of the device, and, for certain features to the end of effecting the desired combination for the purpose of the present invention. The construction of the particular switch 74 selected for illustration may be similar to that more fully disclosed in my copending application Serial No. 263,589, filed March 23, 1939.

For the purpose of the present description, suffice it to state that the particular switch shown in the drawings comprises a pair of contacts 76 and 77 insulated from each other by insulating strips 78 which with the contacts are secured together and in insulated relation in a switch frame 79 of generally channel-shaped cross-section. A ferrule 80 is secured to the switch frame 79, and this ferrule 80 is slotted to receive a switch operating lever 82 which is pivoted to the ferrule 80 or to the switch body by a pin 83. The switch operating lever 82 is of generally bell crank form. One arm 84 of the lever is pivoted 25 on the pin 72 in the slot or bifurcation 85 in the member 70.

The other arm 86 of the lever 82 has a flag or indicator member 87 provided with a colored or appropriately marked portion 88 which, when the device is set or cocked in operating position, is displayed through an opening 89 in the front wall 90 of the housing 20 to indicate that the device is in operating position. During the cocking operation and when the electromagnet is de-energized to close the valve 12, the indicator portion 88 of the member 87 is moved out of register with the opening 89 so that a person may ascertain at a glance from outside the housing 20 the condition of the device.

A coiled spring 92 connected at one end at 93 to the base or wall 23 of the housing 20 and, at its opposite end at 94 to one of the arms of the actuator member 22, maintains the actuator member 22 yieldingly in the position shown in Figure 2, and returns this member to this position following the cocking or setting operation. A spring 96, coiled about the stem 62 and interposed between the spring seating member 64 and the member 70, is held compressed as shown in Figure 5 when the actuator member 22 is pressed inwardly to move the armature 60 to attracted position against the pole ends of the magnet frame 26 and the electromagnet is energized to hold the armature in attracted position. Deenergization of the electromagnet releases the armature, and the spring 96 returns the member 70 to its outwardly projected position as shown in Figure 2, or if the device is cocked and the electromagnet is not energized or, for any reason, fails to hold the member 70 in cocked position, the spring 96 returns this member and the stem 62 to outwardly projected position with the movement of the actuator member 22 to such position.

The switch 74 is pivoted in the forked inner end of the actuator member 22 on a pin 98, and the outward movement of the actuator member 22 is limited, for example, by a cotter pin 99. This pin 99 is shown as bent at 100 around one edge of the actuator member or lever 22 to prevent the pin from turning and interfering with the full outward projection of the lever.

The pivotal movement of the switch arm 82

relative to the switch 74 is adapted to actuate the roller contact 105 of the toggle switch 74 into and out of contact with the arcuate contact edges 106 of the contacts 76 and 77 to open and close the circuit 19 for the valve 12. The arm 108 of the switch arm 82 cooperates with the toggle roller actuating mechanism, and as the inner end of the arm 108 moves past center with respect to a line drawn through the axis of the roller 105 and the pivot 83, the spring 110 snaps the roller contact 105 from one position to the other with a snap action.

Mounted within the housing 20, for example, on the inner side of the back of the housing is an insulating terminal block 115 supporting terminal members 116 and 117 in insulated relation. The contact 76 is connected by a lead 118 and terminal screw 119 to the terminal member 117, and the contact 77 is connected by a lead 120 and terminal screw 121 to the terminal member 116. The conductors 19 of the circuit for the valve 12, which are insulated at 122, enter the housing 20 through an insulating grommet 124. One of the conductors 19 is connected by a terminal screw 125 to the terminal member 116. The other conductor 19 is connected by a terminal screw 126 to the terminal member 117.

When the roller contact 105 is engaged with the contacts 76 and 77 as shown in Figure 5, the circuit 19 is closed, thereby energizing the valve 12 to open and hold this valve in open position for supplying fuel to the burner 10. When the roller contact 105 is snapped to its opposite portion as shown in Figure 2, the circuit 19 is opened or interrupted, thereby releasing the valve 12 for movement, for example, by a spring (not shown) to closed position, shutting off the supply of fuel to the burner.

For purposes of illustration, one set of contacts 76, 77 has been shown. It is to be understood that any desired number of contacts may be employed—for example, an additional contact at the opposite end of the arcuate track of the toggle switch for a three wire circuit. Moreover, if desired, one pair of contacts may be employed at each of the opposite ends of the arcuate track of the toggleswitch, so that one pair of contacts is bridged when the switch is in one position and a second pair bridged when the switch is in the other position.

A thermostat, limit switch, or other condition-responsive device may be provided in the circuit 19 for the valve 12 within the scope of the present invention. Such a device would operate to open 55 the circuit for this valve so that the valve will close upon the temperature rising above a predetermined value or upon some other abnormal or malfunctioning of the apparatus.

To start the operation of the system, the following sequence is followed:

The actuator member or cocking lever 22 is pressed inwardly from the position shown in Figure 2 by engaging the button 24 with the hand or fingers imparting pressure thereto. The switch 74 and the switch operating arm 82, as well as the stem 62, are moved inwardly with this inward movement of the actuator member 22 until the armature is cocked or set into attracted position against the pole ends of the magnet frame 26.

The pilot burner 36 is lighted, or, having been lighted, heats the thermocouple, and the lever 22 is held pressed inwardly until the heat of the pilot flame on the thermocouple has energized

the electromagnet sufficiently so that it will hold the armature 60 thereto.

When the electromagnet is energized sufficiently to hold the armature 60 in attracted position, the lever or cocking member 22 is released, and the stem 62 remains in cocked position holding the end of the switch arm 84, which is pivoted at 72, in the position shown in Figure 5. Release of the actuator lever 22 allows the spring 92 to return this lever to its outwardly projected position as shown in Figure 5. The switch 74, moving outwardly with the lever, acts through its pivotal connection with the lever at 98 and its pivotal connection with the switch operating arm 82, at 83, to swing this arm 82 in a clockwise direction from the position shown in Figure 2 to the position shown in Figure 5. This actuates the roller contact 105 into contact with the contacts 76 and 77 with a snap action to close the circuit 19 for the valve 12. As a result, this valve is actuated to open position and held in open position to pass fuel to the main burner as long as the parts are in the positions last described.

If the pilot burner is not lighted to produce the thermo-electric current for holding the armature 60 in attracted position upon setting the same to that position by the cocking lever 22, the armature 60 and the stem 62 and member 70 will move outwardly with the actuator member 22 when the same is released after being actuated to set the armature in attracted position. As a result, the switch operating arm 82 will move outwardly with the other parts and there will be no swinging or pivotal movement of this arm with respect to the switch 74 to actuate the roller contact 105 into engagement with the contacts 76 and 77. If, after the parts are set as shown in Figure 5 and the pilot burner is lighted to hold the parts in the positions shown in this figure, the pilot burner is extinguished, the armature 60 is released. The spring 96 then operates to move the armature to retracted position and the stem 62 and member 70 in a downward direction as shown in the drawings. This swings the switch operating arm 82 in a counterclockwise direction through the pivotal connection at 72 and actuates the contact roller to position out of engagement with the contacts 76 and 77, as shown in Figure 2. This opens or interrupts the circuit 19, and the valve 12 operates to closed position to shut off the supply of fuel to the pilot burner.

I contemplate within the scope of my present invention removing or omitting the spring 92. With this spring 92 removed or omitted and the armature in attracted position, the switch may be actuated to "on" or "off" position by manually actuating the lever or actuator 22 out or in respectively.

The embodiment of the invention shown in the drawings is for illustrative purposes only, and it is to be expressly understood that said drawings and the accompanying specification are not to be construed as a definition of the limits or scope of the invention, reference being had to the appended claims for that purpose.

I claim:

1. In a switch of the class described, in combination, an actuator member movable between cocking and released positions, a second member adapted to be cocked by movement of said actuator member to cocking position, means for holding said second member in cocked position, an insulating contact supporting body carried by said actuator member for movement with said actuator member to its cocking and released

positions, first contact means carried by said contact supporting body, a switch operating arm pivoted to said second member and to said contact supporting body, and second contact means operatively connected to said switch operating arm and actuated into contact with said first contact means by pivotal movement imparted to said arm by movement of said actuator member to released position with said second member held in cocked position, said second contact means being actuated to position out of contact with said first contact means by pivotal movement imparted to said arm by movement of said second member to retracted position.

2. In a switch of the class described, in combination, an actuator member movable between cocking and released positions, a second member adapted to be cocked by movement of said actuator member to cocking position, means for holding said second member in cocked position, an insulating contact supporting body carried by said actuator member for movement with said actuator member to its cocking and released positions, first contact means carried by said contact supporting body, a switch operating arm pivoted to said second member and to said contact supporting body, second contact means, and a toggle connection between said switch operating arm and said second contact means and operable to actuate said second contact means into contact with said first contact means by pivotal movement imparted to said arm by movement of said actuator member to released position with said second member held in cocked position, said toggle connection actuating said second contact means to position out of contact with said first contact means by pivotal movement imparted to said arm by movement of said second member to retracted position.

3. In a switch of the class described, in combination, an actuator member movable between cocking and released positions, a second member adapted to be cocked by movement of said actuator member to cocking position, means for holding said second member in cocked position, an insulating contact supporting body carried by said actuator member for movement with said actuator member to its cocking and released positions, first contact means carried by said contact supporting body, a switch operating arm pivoted to said second member and to said contact supporting body, second contact means operatively connected to said switch operating arm and actuated to position out of contact with said first contact means by pivotal movement imparted to said arm by movement of said second member to released position, and a spring operative to move said actuator member to released position, the movement of said contact supporting body with said actuator member to its released position with said second member held in cocked position swinging said switch operating arm in a direction to move said second contact means into contact with said first contact means.

4. In a switch of the class described, in combination, an actuator member movable between cocking and released positions, a second member adapted to be cocked by movement of said actuator member to cocking position, means for holding said second member in cocked position, an insulating contact supporting body carried by said actuator member for movement with said actuator member to its cocking and released positions, first contact means carried by said contact supporting body, a switch arm pivoted to

second member and to said contact supporting body, second contact means, a toggle connection between said switch operating arm and said second contact means and operable to actuate said second contact means to position out of contact with said first contact means by pivotal movement imparted to said arm by movement of said second member to released position, and a spring operative to move said actuator member to released position, the movement of said contact supporting body with said actuator member to its released position, with said second member held in cocked position, swinging said switch operating arm in a direction to move said second contact means into contact with said first contact means.

5. In a switch of the class described, in combination, a guide bracket, an actuator member guided in said bracket for rectilinear movement between cocking and released positions, a second member having rectilinear movement between cocked and released positions and adapted to be cocked by movement of said actuator member to cocking position, means for holding said second member in cocked position, a contact supporting body attached to the actuator member for movement with said actuator member to its cocking and released positions, first contact means carried by said contact supporting body, a switch operating arm pivoted to said second member in position spaced from the attachment of said contact supporting body to said actuator member in the direction of rectilinear movement of said actuator member and said second member, a pivotal connection between said switch operating arm and said contact supporting body, and second contact means operatively connected to said switch operating arm and actuated into contact with said first contact means by separation of the attachment of said contact carrying arm to said actuator member from the pivotal connection between said switch operating arm and said second member.

6. In a switch of the class described, in combination, a guide bracket, an actuator member guided in said bracket for rectilinear movement between cocking and released positions, a second member having rectilinear movement between cocked and released positions and adapted to be cocked by movement of said actuator member to cocking position, means for holding said second member in cocked position, a contact supporting body attached to the actuator member for movement with said actuator member to its cocking and released positions, first contact means carried by said contact supporting body, a switch operating arm pivoted to said second member in position spaced from the attachment of said contact supporting body to said actuator member in the direction of rectilinear movement of said actuator member and said second member, a pivotal connection between said switch operating arm and said contact supporting body, second contact means, and a toggle connection between said switch operating arm and said second contact means and operable to actuate said second contact means into contact with said first contact means by separation of the attachment of said contact carrying body to said actuator member from the pivotal connection between said switch operating arm and said second member.

7. In a switch of the class described, in combination, a guide bracket, a forked actuator member guided in said bracket for rectilinear move-

ment between cocking and released positions and having spaced arms having slots therein, a second member having rectilinear movement between cocked and released positions and adapted to be cocked by movement of said actuator member to cocking position, said second member being positioned between the arms of said actuator member and having a pin operable slidingly in the slots in said arms, means for holding said second member in cocked position, a contact supporting body attached to the actuator member for movement with said actuator member to its cocking and released positions, first contact means carried by said contact supporting body, a switch operating arm pivoted to said second member in position spaced from the attachment of said contact supporting body to said actuator member in the direction of rectilinear movement of said actuator member and said second member, a pivotal connection between said switch operating arm and said contact supporting body, and second contact means operatively connected to said switch operating arm and actuated into contact with said first contact means by separation of the attachment of said contact carrying body to said actuator member from the pivotal connection between said switch operating arm and said second member.

8. In a switch of the class described, in combination, a guide bracket, a forked actuator member guided in said bracket for rectilinear movement between cocking and released positions and having spaced arms having slots therein, a second member having rectilinear movement between cocked and released positions and adapted to be cocked by movement of said actuator member to cocking position, said second member being positioned between the arms of said actuator member and having a pin operable slidingly in the slots in said arms, means for holding said second member in cocked position, a contact supporting body attached to the actuator member for movement with said actuator member to its cocking and released positions, first contact means carried by said contact supporting body, a switch operating arm pivoted to said second member in position spaced from the attachment of said contact supporting body to said actuator member in the direction of rectilinear movement of said actuator member and said second member, a pivotal connection between said switch operating arm and said contact supporting body, second contact means, and a toggle connection between said switch operating arm and said second contact means and operable to actuate said second contact means into contact with said first contact means by separation of the attachment of said contact carrying body to said actuator member from the pivotal connection between said switch operating arm and said second member.

9. In a switch of the class described, in combination, an actuator member movable between cocking and released positions, selectively operable holding means, a switch operating member adapted to be cocked to position to be held by said holding means by movement of said actuator member to cocking position, said actuator member being movable to released position free of said switch operating member and said switch operating member being movable to released position upon release of said holding means, first contact means carried by said actuator member for movement with

said actuator member to its cocking and released positions, second contact means movable into and out of contact with said first contact means, and an operating connection between said switch operating member and said second contact means for moving said second contact means into contact with said first contact means by movement of said actuator member to released position with said switch operating member held in cocked position by said holding means and operative to move said second contact means out of contact with said first contact means by movement of said switch operating member to released position.

10. In a switch of the class described, in combination, an actuator member movable between cocking and released positions, selectively operable holding means, a switch operating member adapted to be cocked to position to be held by said holding means by movement of said actuator member to cocking position, said actuator member being movable to released position free of said switch operating member and said switch operating member being movable to released position upon release of said holding means, first contact means pivoted to said actuator member for movement with said actuator member to its cocking and released positions, second contact means movable into and out of contact with said first contact means, and a toggle connection between said switch operating member and said second contact means for moving said second contact means into contact with said first contact means by movement of said actuator member to released position with said switch operating member held in cocked position by said holding means and operative to move said second contact means out of contact with said first contact means by movement of said switch operating member to released position.

11. In a switch of the class described, in combination, an actuator member movable between cocking and released positions, selectively operable holding means, a switch operating member adapted to be cocked to position to be held by said holding means by movement of said actuator member to cocking position, said actuator member being movable to released position free of said switch operating member and said switch

operating member being movable to released position upon release of said holding means, first contact means pivoted to said actuator member for movement with said actuator member to its cocking and released positions, second contact means movable into and out of contact with said first contact means, and a toggle connection between said switch operating member and said second contact means for moving said second contact means into contact with said first contact means by movement of said actuator member to released position with said switch operating member held in cocked position by said holding means and operative to move said second contact means out of contact with said first contact means by movement of said switch operating member to released position, the toggle connection between said switch operating member and said second contact means including a switch operating arm pivoted to said switch operating member.

15. In a switch of the class described, in combination, an actuator member having rectilinear movement between cocking and released positions, a second member having rectilinear movement between cocked and released positions and adapted to be cocked by movement of said actuator member to cocking position, means for holding said second member in cocked position, an insulating contact supporting body carried by said actuator member for movement with said actuator member to its cocking and released positions, first contact means carried by said contact supporting body, a switch operating arm pivoted to said second member and to said contact supporting body, and second contact means operatively connected to said switch operating arm and actuated into contact with said first contact means by pivotal movement imparted to said arm by rectilinear movement of said actuator member to released position with said second member held in cocked position, said second contact means being actuated to position out of contact with said first contact means by pivotal movement imparted to said arm by rectilinear movement of said second member to retracted position.

RICHARD K. ENGHOLDT.
